(57) **CLAIM**

The ornamental design for a pet feeder table, as shown and described.

DESCRIPTION

FIG. 1 is a front, top perspective view of a pet feeder table, showing my new design;

FIG. 2 is a rear, bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is another front, top perspective view of the pet feeder table, shown in an alternative position;

FIG. 10 is a front elevation view thereof;

FIG. 11 is a left side elevation view thereof;

FIG. 12 is a top plan view thereof; and,

FIG. 13 is a bottom plan view thereof.

The broken lines in the figures illustrate portions of the pet feeder table that form no part of the claimed design.
